(57) **CLAIM**

The ornamental design for a handlebar, as shown and described.

DESCRIPTION

FIG. 1 is a top, front, right perspective view of a handlebar, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines of even length shown in the drawings illustrate portions of the handlebar that form no part of the claimed design.

1 Claim, 7 Drawing Sheets
